UNITED STATES PATENT OFFICE.

WILLIAM D. FORSYTH, OF YOUNGSTOWN, OHIO.

FIREPROOF FLOOR SYSTEM.

1,038,551.

Specification of Letters Patent. Patented Sept. 17, 1912.

Application filed July 17, 1911. Serial No. 638,791.

To all whom it may concern:

Be it known that I, WILLIAM D. FORSYTH, a citizen of the United States, residing in Youngstown, in the county of Mahoning, in the State of Ohio, have invented new and useful Improvements in Fireproof Floor Systems, of which the following is a specification.

My invention relates to new and useful improvements in fire proof floor systems adapted for the use and construction of buildings.

My invention consists of means made from expanded metal for constructing fire proof floor systems with air spaces therein when said means are used in connection with concrete; also means made from expanded metal and used in connection with concrete for reinforcing fire proof floor systems so as to permit the construction of such floor systems without the use of centering devices; also a reinforced metallic-cellular floor system hereinafter described.

In the accompanying drawings forming part of this specification, like reference figures refer to like parts throughout.

Figure 1 is a vertical cross section of Fig. 3 on section line A—A. Fig. 2 is a vertical longitudinal cross section of Fig. 3 on section line B—B. Fig. 3 is a plan view of a section of my improved reinforced metallic-cellular floor system, but the concrete has not been placed upon the metallic parts thereof and with the air spaces formed in trough-like shape. Fig. 4 is a plan of a sheet of expanded metal from which the troughs for forming air spaces in the floor system are made. Fig. 5 is an end view of the sheet of expanded metal shown in Fig. 4. Fig. 5 is a perspective view of the trough-like metallic structure used for forming air spaces in my improved floor system, said trough-like structure being made of expanded metal. Fig. 7 is a section of the joint of the trough-like structure shown in Fig. 6 on section line c—c. Fig. 8 is a vertical cross section of Fig. 10 on section line E—E, concrete being shown in Fig. 8 massed upon the metallic parts thereof, but in Fig. 10 no concrete has yet been placed upon such metallic parts. Fig. 9 is a longitudinal sec-

tion of Fig. 10 on section line D—D, concrete having been placed upon the metallic parts in Fig. 9, but no concrete having been placed upon the structure shown in Fig. 10. Fig. 10 is a plan view of the metallic parts of my improved floor system, with the same made ready for the placing of concrete thereon and with the air spaces formed therein in the shape of trough-like boxes. Fig. 11 is a perspective view of one of the boxes used in my improved floor system for the purpose of forming air spaces therein, said trough-like boxes being made from expanded metal. Fig. 12 is a plan view of a sheet of expanded metal from which are formed the trough-like boxes shown in perspective in Fig. 11. Fig. 13 is an end view of the expanded metal sheet shown in Fig. 12. Fig. 14 is a section of expanded metal used for closing the ends of the trough-like boxes shown in Fig. 11. Fig. 15 is a plan view of the bottom of trough-like box shown in Fig. 11. Fig. 16 is a plan view of a section of expanded metal placed between the beams entering into the construction of my improved floor system upon which are placed the trough-like structure or the trough-like box for the purpose of forming air spaces in my floor system. Fig. 17 is an end view of the sheet of expanded metal shown in Fig. 16.

My improved floor system may be constructed in those buildings in which fire proof floor systems are installed, and preparatory thereto, floor beams are placed in position which afford means for attaching thereto, what may be termed the base plate of my improved floor system shown in plan and end views in Figs. 16 and 17 of the drawing. The beams of the building entering into the construction preferably made up of I beams, 1, shown in the various figures of the drawings having the standard flanges, but said floor beams may be made of any construction provided they have an abutment which performs the function of the flanges of the I beams or other means to which the base plate of my system as herein described may be attached or supported.

Base plate 2, Figs. 1, 16 and 17 is made of sheets of ribbed expanded metal; it has two

series of ribs, 2', 2' constituting one series of ribs, the rib 2'', the other series, which are entire and extend longitudinally the length of the sheet, they are connected by reticulated portions, 2''', 2''', which are produced by the expansion of the sheet after the same has been properly slotted. Ribs 2', 2' may be of any dimension and any number and at any location in the base plate so as to provide for locating and fixing the position of troughs 3, Fig. 6, or box 4, Fig. 11, provided one of said ribs 2' is at one edge of the sheet so as to permit of the interlocking thereof with rib 2'' of any base plate, but rib 2''

10 must always be located at one edge of base plate 2 and be of such size as to fit over edge rib 2' of a separate base plate so as to permit the interlocking of said base plates. Said base plates are placed upon the

15 abutments or flanges of floor beams 1 in such number as to fill the opening between the main and cross beams of the floor system so as to be in a position to receive and hold concrete on the top thereof and to be plastered with cement or other plaster on the bottom thereof.

3', Fig. 4, is a sheet of metal from which trough 3, Fig. 6, is made; said sheet 3' is provided with longitudinal members 3'' and 30 3''', 3''', 3''', 3'' is an entire metal longitudinal member extending the length of the sheet and is of such width as to be capable of being formed into rib 3^a, Fig. 4, said longitudinal member 3'' is connected by a 35 reticulated portion of the sheet 3' to the adjacent longitudinal member 3'''. Said last mentioned longitudinal member 3'''' is connected by another reticulated portion to another longitudinal member 3' which in turn is connected to reticulated portion of the sheet with the longitudinal entire metal member 3''' at the edge of said sheet. Said longitudinal members 3''' are of such size and dimension as to be capable of being pressed 40 into ribs 3^b, 3^b, shown in end view in Fig. 5, the edge rib 3^b is of such size and dimension as to be capable of being inserted in rib 3^a, so that several sheets, 3', may be joined together by means of their respective ribs 3^a 45 and edge rib 3^b, so as to permit the making of trough 3 of any length that may be desired in the construction of my floor system.

Sheets 3' having been formed with their ribs 3^a and 3^b as aforesaid, said ribs being 50 connected by reticulated sections of said sheet, they are by suitable presses and dies pressed into a U-shaped section as shown embodied in trough 3 in Fig. 6. Where a trough longer than that which may be 55 formed by a single sheet is desired, then two troughs formed of single sheets are connected by means of rib 3^a of one being placed over edge rib 3^b of a second, as shown at section line c—c in Fig. 6, the end view of

the joint thus formed being shown in Fig. 7. 65 The troughs 3 being thus formed are placed between ribs 2', 2' of base plate 2, as shown in section Figs. 1 and 2 and in plan in Fig. 3. The structure thus formed by the placing of base plate 2 between the floor beams 1 and 70 the placing upon base plate 1 of the troughs 3, is ready for the reception of concrete to be placed upon the top thereof and for the reception of plaster being placed on the bottom thereof as shown in Fig. 1.

75 If additional reinforcements be desired, then bars 5, 5, 5, may be placed parallel to the longitudinal axes of troughs 3, as shown in Figs. 1, 2 and 3, sections of said bars 5, being shown in Fig. 1 and the entire 80 bars being shown in Figs. 2 and 3.

Box 4 in Fig. 11 is made from a sheet of metal, 6, which has entire longitudinal members 6', 6', 6', connected by reticulated portions as shown in Fig. 12 in plan view and 85 Fig. 13 in end view, the ribs being shown in both figures. Said ribs 6', 6', 6', are connected by reticulated sections 7, 7, said ribs 6' are of the same size and dimension; the reticulated sections 7 are formed in any 90 suitable manner so as to permit of the expansion of the sheet from which it is made. While in Figs. 12 and 13 said sheet is shown with three ribs and two reticulated sections connecting the same, where desired the number of ribs and reticulated sections may be increased. When said sheet 6 has been expanded and ribs 6', 6', 6', have been formed therein by means of suitable presses and dies, it is formed in a U shaped section 100 4' as shown in Fig. 11 with the end ribs of said boxes 6', 6', being capable of receiving a sheet of expanded metal 8, as shown in Fig. 15, so that box 4 of Fig. 11 shall be closed on five sides, the bottom alone being 105 open.

Fig. 14 is a plan view of sheet 8 of expanded metal, which may be expanded metal of any character, said sheet 8 shall be of such size and dimension as to be capable of being inserted in end ribs 6', 6', of box 4.

110 My floor system as constructed by the use of box 4, Fig. 11, is shown in the cross section in Fig. 8 and the longitudinal cross section Fig. 9 and in plan in Fig. 10. It is 115 constructed by placing base plate 2 between the floor beams of the floor system and then placing therein between the ribs 2', 2', of said base plate 2, boxes spaced with reference to each other substantially as shown in 120 Fig. 10. As thus prepared my improved floor system is ready for the reception of concrete on the top thereof and plaster on the bottom thereof.

125 Bars 5, 5, 5, may be used in connection with said boxes and base plates, and bars 9, 9, 9, may also be used, placing the same substantially at right angles to bars 5, 5, 5,

in connection with said base plate 2 and box 4, said bars being placed in position whether one or both series thereof be used before concrete is placed upon said base plates and boxes.

Troughs 3 and box 4 and the expanded metal composing them as well as the base plates 2, are of such construction as to permit the keying of some mortar or plaster on all sides of said boxes, troughs and base plates, and when properly applied form in my improved floor system air cells in which the ribs strengthen and stiffen the system and in connection with the concrete the bars which may be used therewith afford a means of constructing a floor system which is fire proof, light in weight, strong and durable and cheap of construction.

The ribs of the floor plates afford a weight sustaining means which will permit the placing of said base plates between the floor beams of the floor construction, constructed according to my invention as herein described, which will sustain the weight of the boxes and troughs and the concrete placed around and on top of the same without the necessity of supporting centers or centering device. This characteristic of my base plates cheapens and simplifies the construction of fire proof floor systems in building. The difference in weight of the troughs or boxes, as the case may be, as the same are used in floor construction in accordance with my invention herein described, also lessens the weight of the floor system as compared with the floor system constructed by the use of tile or terra cotta or solid metal means of making air cells, the air cells permitted by my construction being made with the least possible amount of metal and weight as compared with constructions heretofore in use.

What I claim as my invention is:

1. In a reinforced concrete floor system a sectional metallic trough having curved ribs transverse the axis thereof; said ribs being connected with each other by sections of reticulated metal of said trough; said trough being provided with means at the ends thereof for interlocking, end to end, with like metallic troughs in said system.

2. In a reinforced concrete floor system, a metallic trough having curved ribs transverse the axis thereof connected by sections of reticulated metal, said ribs being at the ends of said trough and intermediate said ends and means insertible in the end ribs of said trough for closing the ends thereof.

3. In a reinforced concrete floor system, the combination of the floor beams of the building with metallic sectional base plates having entire longitudinal ribbed sections connected by reticulated sections and means of interlocking said base plates; sectional

metallic interlocking troughs, having curved 65 ribbed sections with ribs transverse their axes and means for interlocking the sections thereof, mounted upon said base plates; and plastic cementitious material applied to said floor beams, base plates and troughs so 70 as to form air spaces within said troughs and the ceiling and floor of rooms in said building respectively below and above said floor system.

4. In a reinforced concrete floor system, 75 the combination of the floor beams of the building with metallic sectional base plates having entire longitudinal ribbed sections connected by reticulated sections and means of interlocking said base plates; sectional 80 metallic interlocking troughs having curved ribbed sections with ribs transverse their axes and means for interlocking the sections thereof, mounted upon said base plates; reinforcing bars placed above said base plates, 85 between said floor beams and said troughs, and between said troughs, parallel to the axes of said troughs; and plastic cementitious material applied to said floor beams, base plates and troughs so as to form air 90 spaces within said troughs and the ceiling and floor of rooms in said building respectively below and above said floor spaces.

5. In a reinforced concrete floor system 95 the combination of floor beams of the building with metallic sectional base plates having entire longitudinal ribbed sections connected by reticulated sections and means of interlocking the sections thereof; metallic troughs closed at both ends thereof mounted 100 upon said base plates so as to form spaces, for the reception of cementitious material, plastic cementitious material placed upon said floor beams, base plates, and end closed metallic troughs so as to form air spaces 105 within said troughs and the ceiling and the floor of the rooms in said building below and above said floor system respectively.

6. In a reinforced concrete floor system, 110 the combination of floor beams of the building with metallic sectional base plates having entire longitudinal ribbed sections connected by reticulated sections and means of interlocking the sections thereof; metallic troughs closed at both ends thereof 115 mounted upon said base plates so as to leave spaces for the reception of cementitious material on all sides of said end closed troughs; and bars placed above said base plates in the spaces between said end closed troughs, said 120 bars being in two series and at right angles to each other; the plastic cementitious material placed upon said floor beams, base plates, and closed metallic troughs, so as to form air spaces in said end closed metallic 125 troughs and the ceiling and the floor of the rooms in said building below and above said floor system respectively.

7. In a reinforced concrete floor system a sectional metallic trough having at its ends and intermediate said ends and transverse its axis curved ribs of similar cross section, 5 and connected with each other by reticulated metal sections of said trough; one end rib being larger in cross section than the other end rib; the surface of the large end rib inside of its curve being substantially

equal in area to the surface of the small end 10 rib outside of its curve.

In testimony whereof I have signed this specification in the presence of two subscribing witnesses.

WILLIAM D. FORSYTH.
